UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

TRANSFORMER.

1,331,068.

Specification of Letters Patent. Patented Feb. 17, 1920.

Application filed March 6, 1917. Serial No. 152,561.

To all whom it may concern:

Be it known that I, SVEND E. JOHANNESEN, a citizen of the United States, residing at Pittsfield, in the county of Berkshire, State of Massachusetts, have invented certain new and useful Improvements in Transformers, of which the following is a specification.

My invention has for its object the provision of a transformer having good electrical properties and in which the materials, and particularly the windings, are advantageously arranged.

I have shown my invention embodied in a type of transformer similar to that shown in patent to Hall #861,029, particularly as regards the form of the core which is provided with a middle leg the ends of which are connected by a plurality of outer legs which complete the magnetic path of the middle leg and which are spaced therefrom to form an annular space within which the primary and secondary windings are disposed.

It is common practice in building up the windings of a transformer to segregate, more or less, the primary and secondary windings, and it has hitherto been proposed to build up the windings of a transformer having a core of the form above indicated, by interposing, radially, a primary winding between an outer and an inner secondary winding. It is well known that, other things being equal, the better the primary and secondary windings are intermixed, the lower will be the reactance of the transformer, and inasmuch as the windings of the transformer just referred to are well intermixed, the same has a low reactance.

But while such an arrangement of the windings is satisfactory as regards the reactance of the transformer, it is unsatisfactory from the standpoint of the best utilization of the winding space, since the two insulating spacing members which it is necessary to provide between the primary winding and the two secondary windings occupy just so much valuable winding space. It has also been proposed to form the windings of a single primary and a single secondary winding separated by a cylindrical insulating spacing member. While such an arrangement well utilizes the winding space, the transformer has an undesirably high

reactance, since the windings are poorly intermixed.

In accordance with my invention, I utilize the winding space to good advantage by providing a single primary winding separated from a single secondary winding by a single insulating spacing. Instead, however, of providing plain cylindrical windings with a plain cylindrical insulating space or member between the two as has hitherto been the common practice, I nest one winding within the other, so that a section of the insulating space between the two concentric windings formed by a plane passing through the axis of the transformer instead of being bounded by straight lines at its sides, gives a trace having the appearance of a distorted curve. Thereby a good intermixing of the windings is produced, and hence a low reactance; at the same time, there is but a single insulating space, and while it occupies more space than would a cylindrical insulating space of the same thickness, it is but little more and I have found that the gain effected in the lowering of the reactance much more than compensates for the slight loss in winding space due to the increase of the length of the cross section of the insulating space.

For a fuller understanding of my invention, reference may be had to the accompanying drawing showing several modified forms thereof, and in which:

Figure 1 is a perspective view of a transformer embodying my invention with the windings partially broken away;

Fig. 2 is a side view showing one of the legs of the core of the transformer, with the windings in section; and

Figs. 3, 4 and 5 are views similar to Fig. 2 showing modified forms of my invention.

Referring now to the drawings, and first to Figs. 1 and 2, in which I have shown what I at present consider the preferred form of my invention, 10 is a core of a transformer similar to that shown in the Hall patent above referred to, and which is provided with a restricted middle leg (not shown in the drawing) formed from one of the sides of each of a number of laminated units such as shown in Fig. 2. The outer legs 10^a, 10^b, 10^c and 10^d of the units are spaced from the middle leg to form an annular winding space 11 in which the pri-

mary and secondary windings are segregated, the primary winding 12 being concentric with and nested within the secondary winding 13. In the form of my invention shown in Figs. 1 and 2, the side of the primary winding adjacent the secondary winding presents a convex appearance while the adjacent side of the secondary winding is concave, the two being separated by an insulating member, 14, the cross section of which determined by a plane passing through the axis of the transformer as shown in Fig. 2 is curved as shown. In this manner, as will be obvious, the windings are well intermixed and therefore the transformer has a low reactance; at the same time the winding space is utilized to good advantage. The primary and secondary windings are insulated from the core 20 of the transformer by a member 15.

Fig. 3 shows a modified form of my invention in which the nesting of the windings is effected, by making one winding, here shown as the primary winding 12^a, T-shaped in cross section, and providing two distinct secondary windings 13^a on either side of the stem of the T.

Fig. 4 shows another modified form of my invention in which the primary winding 12^b is rectangular in cross section and is nested within a U-shaped secondary winding 13^b, which incloses the primary winding on three sides.

Fig. 5 shows still another form of my invention in which a single primary winding 12^c, is nested within two secondary wind-

ings, 13^c, the primary and secondary being separated by an insulating member made up in cross section by two straight members extending obliquely from the ends of the winding space to the middle of one of the sides.

While I have illustrated my invention in connection with a particular form of transformer, it will, of course, be understood that it is not limited thereto in its application, 45 but may advantageously be used in connection with any transformer.

In accordance with the provisions of the patent statutes, I have described the principle of operation of my invention, together 50 with the apparatus which I now consider to represent the best embodiment thereof; but I desire to have it understood that the apparatus shown is only illustrative and that the invention can be carried out by other 55 means.

What I claim as new and desire to secure by Letters Patent of the United States is:

In a transformer, the combination with a distributed core having a restricted middle leg, of concentric exteriorly cylindrical primary and secondary windings surrounding said leg, and an insulating member separating said primary and secondary windings into intermingled portions in a predetermined fashion whereby the trace of said member in a plane containing the transformer axis is a distorted curve.

In witness whereof, I have hereunto set my hand this 27th day of Feb., 1917.

SVEND E. JOHANNESEN.
